UNITED STATES PATENT OFFICE.

WALLACE HOYT MITCHELL AND JOSEPH HIRAM THOMAS, OF MANSFIELD, OHIO.

CUFF-BUTTON.

1,199,707.

Specification of Letters Patent. Patented Sept. 26, 1916.

Application filed March 17, 1916. Serial No. 84,816.

To all whom it may concern:

Be it known that we, WALLACE HOYT MITCHELL and JOSEPH HIRAM THOMAS, citizens of the United States of America, 5 residing at Mansfield, in the county of Richland and State of Ohio, have invented certain new and useful Improvements in Cuff-Buttons, of which the following is a specification.

10 This invention primarily relates to cuff buttons or the like.

The essential object of the present invention consists in constructing a rigid connecting post to join or unite buttons for use 15 in fastening or linking the ends or edges of cuffs or the like together in such a manner as to permit of the entering, inserting and placing of the buttons in proper position in the button holes of the cuff or the like and 20 their removal therefrom, in an easy, quick and convenient manner.

A further object is to provide means of interlocking the cuff buttons to a cuff or the like to prevent them from turning or 25 becoming disengaged from the button holes after being inserted therein.

A further object of the invention consists 30 in constructing a post that is adapted to slidably engage the button holes of a cuff or the like to permit longitudinal movement therein; but which prevents lateral movement.

A further object is the construction of 35 a post for joining buttons which are used for the purpose of linking cuffs or the like that is simple in construction and adapted to maintain the buttons in a predetermined, rigid relation with respect to each other.

These and other objects are attained by the 40 mechanism illustrated in the accompanying drawing in which:—

Figure 1 is an end view (taken on the line $x-x$ of Fig. 3) partly in section of a conventional cuff showing the first step performed to insert one of two connected buttons in the button hole of one edge or side preparatory to linking both edges or sides of the cuff together. Fig. 2 is an end view (taken on the line $x-x$ of Fig. 3) partly in section showing the second step performed to insert the coöperating connected button in the button hole provided in the opposite edge or side of the cuff to link the edges or sides of the cuff together. Fig. 3 is a plan view of a fragment of a cuff showing the body portion of the post in dotted lines in a position at right angles to the slit forming the button hole. Fig. 4 is a fragmentary plan view of a cuff showing the body portion of the post alined with the slit forming the button hole. Fig. 5 is a fragmentary plan view of a cuff showing the button in full lines and the post in dotted lines interlocked at the end of the slit forming the button hole and adjacent to the free ends or 60 edges of the cuff. Fig. 6 is an end view of a folded cuff partly in section showing the method of interlocking the buttons and connecting post to the cuff. Fig. 7 shows detail edge views of the buttons and a vertical elevation of the post in position preparatory to being connected to the buttons by any well known fastening means.

10 This invention primarily relates to cuff buttons or the like.

15 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

20 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

25 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

30 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

35 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

40 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

45 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

50 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

55 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

60 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

65 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

70 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

75 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

80 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

85 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

90 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

95 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

100 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

105 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

110 The essential object of the present invention consists in constructing a rigid connecting post to join or unite buttons for use in fastening or linking the ends or edges of cuffs or the like together in such a manner as to permit of the entering, inserting and placing of the buttons in proper position in the button holes of the cuff or the like and their removal therefrom, in an easy, quick and convenient manner.

In manipulating the completed cuff button to insert it in the button holes of the free ends of sides of a cuff or the like, the user grasps the button and inserts it in the 5 button hole forcing it to enter and slide therein substantially upon a plane with the body of the cuff, the edges of the material forming the button hole are thereby gradually forced into the slot 6 until the button 10 is substantially through the button hole, it is then slightly tipped to permit the edge or side *b* to yield and assume the position shown in Fig. 2. The lower edge or side 2 of the cuff is then folded and the linked co- 15 operative button is inserted in the button hole and forced to enter the button hole substantially on a plane with the body of the cuff until the button is substantially through the button hole, it is then tipped forcing the 20 edge or side *c* to yield and assume its proper and normal position as shown in Fig. 6. The cuff button is then preferably grasped between the thumb and index finger and given a quarter turn to direct the open ends 25 of the slots 11 and 12 toward the free end or edge of the cuff. This operation forces the body portion of the post from the position shown in Fig. 3 (in dotted lines) to the position shown in Fig. 4 (in dotted lines) 30 in alignment with the button hole which permits the post to be slidably moved in the button hole to engage and interlock through the medium of the slots 11 and 12 with the material forming the ends of the 35 button holes as clearly shown in Fig. 6 and at the same time permitting the leg portions 13 and 14 of the post to extend into the button holes of the folded cuff.

When the cuff button is given a quarter 40 turn, as described, the edges of the button holes *a* and *a'* are automatically forced into the slot 6, the edges of the button holes being guided in the slot as the cuff button

is turned by the inclined ends 15 and 16 of the leg portions 13 and 14. When it is 45 desired to remove the cuff button from the cuff or the like, the operation just described is performed in the reverse order.

Attention is called to the fact that the button as described can be changed or 50 altered for use as a stud, collar or dress button and the like without deviating from the spirit of our invention.

We claim:—

1. A link cuff button, comprising two 55 disks, a flat post having the edges thereof tapered and provided with a slot having a flared opening, said slot extending from adjacent the periphery of the disks beyond the center of the disks to form elongated 60 portions which are adapted to fit within and substantially along the entire length of the slits of a cuff to prevent them from turning, said post having its opposite end rounded and cut away to provide slots opening in an 65 opposite direction from that of the first mentioned slot and which are formed by the inner surface of said disks and said edges of the post.

2. An article of manufacture, comprising 70 in combination, two disks, a flat post having its edges tapered to receive and mount said disks; said post having a slot with a flared opening extending from the periphery of the disks, said slot having its closed end 75 located beyond the center of the disks, and the post also being formed to provide parallel slots between the disks with openings opposite to that of the first mentioned slot, said post adapted to be easily turned to 80 fit substantially along the entire length of the slits in the cuff.

In testimony whereof we affix our signatures.

WALLACE HOYT MITCHELL.
JOSEPH HIRAM THOMAS.
